Fifth Sheet of Murray's Improvement
Letters Patent

The Schedule referred to in these Letters Patent and making part of the same contains a description in the words of the said Joseph Morel himself of his improvement in the machine for Drefing Slaves.

Be it known that Joseph Morel of the Town of Murray in the County of Beaver and State of Pennsylvania, has made a new and useful improvement in the machine for Drefing Slaves, called Morel's Slave Driver which is described as follows. This machine consists of the following parts. 1. The Frame. 2. The Knives or cutters. 3. The followers or drivers. 4. The Guide. 5. The gearing. 6. The Regulators or guides. 7. The crucible stone for heating and drying of the ends of the slaves. 1. The frame is made by fastening two iron rods 6 feet long and 6 by 7 inches thick, these are placed from 7 to 10 inches apart and connected by cross pieces which are mortised and tenoned into them. Upon the rods are erected four posts about 3 by 4 inches thick, and of a length according to the kind of iron to be treated, let into the rods by mortise and tenon, having their tops fitted into long beams to project above the plates, with mortises in them to admit keys which secure the plates. On the plates and rods may be secured by bolts and bars. The plates are about 4 feet long 1 by 5 inches thick, secured to the tops of the posts as before described, and connected by cross bars. Between the posts are framed two short horizontal frames let into the posts by mortise and tenon to receive the guides hereafter described. Tables or platforms are constructed near the knives and bars to rest the stones and regulators upon.

2. The knives or cutters are made of good cast sheet flat iron their inner sides and are so placed that they may be brought nearer to or receded farther from each other at pleasure, according to the thickness of the slaves required to be dressed, by means of a bolt and bar at each end of the knifes. They are placed facing at bottom. Between these knives the stones are to be forced

by means of a follower or driver having cog, upon it, into which a pinion works, as herein after described. There are two sets of these pinions, placed parallel to each other in the sills, and well secured by wedges, and keys. 3rd. The followers or drivers are made of wood, in length according to the length of the stone to be dressed 3 by 5 inches thick with cast iron blocks let in the face of the same. These followers work vertically between guides, in grooves, formed in the same to keep the followers, in their true position. 4th. The guides are made of thick plank having grooves on their inner sides for the followers to work in and are secured at top between the plates by means of keys, and at bottom by the before described hinged frames. Between the two guides, and followers, is placed another guide secured by keys & bolts.

5th. The gearing consists of a cog wheel on the crank shaft about 4, or 5 inches in diameter working into another cog wheel of about 2 feet in diameter upon the axis of which is a pinion 4 or 5 inches diameter working into the racks of the followers or drivers, which work up and down between the guides, on the crank shaft is placed a balance wheel of about 300 lbs weight to regulate the motion of the machine. 6th. The regulating or guides consist of small cast iron frames with rollers in them turning on guides, which frames are let into handles of wood, about four feet long and of suitable thickness to give them strength and are used to guide the stone whilst being forced thru them between the pinions. The operator laying hold of the handle and exerting the end of the guides against a small iron pin or projection in the sill which serves as a fulcrum whilst he brings the roller against the stone and regulates it as it passes through between the pinions. 7th. A circular box for lifting and carrying off the end of the stones, is secured on a saddle at the ends of, and across, the frame with a pulley on the same, around which a band passes to the balance wheel; when the stone is to be used, the small cog wheel on the balance-shaft shaft is thrown out of gear by exerting on shifting bar in which it turns. In the forging I have described a machine similar to one which I have used, but the dimensions of the machine may be varies

best circumstance. Operation. The frame to be dropped a little vertically over a row of knives. The counter handle is turned which turns the balance wheel and the small cog wheel on its axle. This turns a large cog wheel which turns the pinion. This again works up the hand gear down the following upon the starve in a perpendicular manner and drops it through between the knives and thus shaves it. The same time the other rack and follower is raised another starve is turned over the other knives and the motion of the machine reversed which turns the second follower and forces the other starve thru the knives, it drops it in a similar manner as before described for the other rack and knives. When the knives are crooked or twisted the operator turns by the guides as before mentioned. This machine may be turned by the power of a single man with ease. It may likewise be used so as to be operated by a horse or other power. It may also be used for dropping spikes and heading.

is a further illustration of my invention I refer to the model and drawing of the same deposited in the Patent Office

Let it be known as my invention and not previously known in the above-mentioned machine is the additional follower and the use of two, the guides at bottom by the horizontal frame, as before described.
